REFRIGERATION

Albert R. Thomas, Evansville, Ind., assignor, by
mesne assignments, to Servel, Inc., Dover, Del.,
a corporation of Delaware

Application November 9, 1934, Serial No. 752,234

14 Claims. (Cl. 62—6)

My invention relates to refrigeration and more particularly to cooling air in a refrigerator compartment. This application relates back for common subject matter to my earlier application 5 Serial No. 643,975, filed November 23, 1932.

It is an object of my invention to provide a cooling element having an adequate extent of surface for maintaining air in a refrigerator compartment at a desired temperature.

10 It is another object to provide a cooling element which may be positioned in the uppermost part of a refrigerator compartment for most advantageous cooling of air in the compartment.

15 A further object is to automatically provide refrigeration responsive to the demand therefor.

Another object is to automatically maintain the temperature of air in a refrigerator compartment at a substantially constant temperature irrespective of variation in heat leakage into the 20 compartment or other variation in heat load.

In accordance with my invention, I provide in a thermally insulated refrigerator compartment a cooling element having a relatively limited surface for contact with air and normally 25 maintained at a substantially constant temperature which is preferably low enough for rapid freezing of water into ice, or the like. I further provide a condensation-evaporation circuit including an evaporator having relatively extensive 30 surface for heat transfer from air in the refrigerator compartment, and a condenser arranged in thermal exchange relation with the low temperature cooling element. I preferably position the extensive surface evaporator above the condenser 35 and in the uppermost part of the refrigerator compartment, and provide for flow of liquid cooling fluid from the condenser to the evaporator by thermosyphonic action responsive to temperature of air to be cooled in the refrigerator 40 compartment.

My invention, together with the objects and advantages thereof, will be better understood upon reference to the following description and accompanying drawings forming a part of this 45 specification, and of which:

Fig. 1 is a front elevation, with portions broken away, of a refrigerator embodying my invention;

Fig. 2 is a fragmentary section taken on line 2—2 in Fig. 1; and

50 Fig. 3 is a section taken on line 3—3 in Fig. 2.

Referring to the drawings, in Fig. 1 I have shown a refrigerator 10 having a thermally insulated storage compartment 11 accessible by means of a door 12, and a lower apparatus 55 compartment accessible by means of a removable

closure member 13. In the storage compartment 11 is a cooling element, indicated generally by the reference numeral 14, which may be part of a refrigeration apparatus, for instance, of a pressure equalized absorption type.

Briefly, a refrigeration apparatus of this type may comprise a generator and absorber interconnected for circulation therebetween of an absorption liquid, and an evaporator interconnected with the absorber for circulation therebetween 10 of an inert auxiliary gas. A refrigerant fluid, soluble in the absorption liquid, is vaporized out of solution by heating in the generator, and the vapor is liquefied in a condenser. The liquid refrigerant is conducted to the evaporator where 15 it evaporates and diffuses into the inert gas, producing refrigeration. In the absorber, the refrigerant vapor is absorbed out of the inert gas into the absorption liquid. The evaporator may be maintained at a substantially constant 20 temperature by thermostatic control of the heating of the generator. The generator may be heated in any desired manner as, for instance, by a gas burner arranged so that the flame is projected into a heating flue which extends 25 through the generator.

In Fig. 1, I have shown in the lower apparatus compartment only enough of a refrigeration apparatus necessary for explanation of the present invention. At the forward end of a generator 30 heating flue 15 is arranged a gas burner 16 so that the flame of the burner is projected into the flue 15. Gas is supplied to the burner 16 from a conduit 17 through a gas filter 18 and a thermostatic valve 19. The latter is operated in 35 a known manner by an expandible fluid thermostat including a capillary tube 21 connected to a sensitive bulb 20 which is located in thermal contact on the cooling element 14; so that the valve 19 is operated responsive to temperature of the 40 cooling element 14. The thermostatic valve 19 may be adjusted by a knob 23 on the upper part of the front baffle plate of the cooling element 14 by means of a flexible cable arrangement 24, of which the lower end may be seen in Fig. 1 and 45 the upper end in Fig. 2.

The cooling element 14 comprises a pipe coil 34 which may be embedded in a metal casting 25. The coil 34 may be formed in a plurality of superposed substantially horizontal U-shaped loops, generally as described in an application Serial No. 645,422 of Sven W. E. Andersson and William R. Hainsworth. The casting 25 provides recesses for ice freezing trays 28. The thermostat bulb 20 is 50 55

preferably located in good thermal contact on the bottom of the casting 25. The casting 25 is formed with a plain outer surface affording relatively limited surface for heat transfer from air 5 in the refrigerator compartment 11.

In accordance with my invention, I provide a further element for cooling the air in the refrigerator compartment 11 and comprising a tube 26 having an extensive heat transfer surface formed 10 by a plurality of fins 27. The finned tube 26 may advantageously be positioned directly above the casting 25 as shown in Figs. 2 and 3. However, the finned tube 26 may be otherwise located and may be of any desired length or configuration 15 depending upon the size of the refrigerator compartment to be cooled, and, therefore, the heat transfer surface necessary. The finned tube 26 may be referred to as an evaporator.

Also embedded in a side wall of the casting 25 20 is a pipe coil 29. The upper end of the pipe coil 29, at the forward end of the casting 25, is connected to the forward end of the finned tube 26 at a point near the upper part of the latter, so that vapor produced in a process hereinafter described 25 may flow from the finned tube 26 into the coil 29. The lower end of the coil 29 is connected through a downwardly looped conduit 30 to the other end of the finned tube 26. One leg 32 of the downwardly looped conduit 30 is provided with a plurality 30 of heat transfer fins 33. The finned tube 26, pipe coil 29, and the loop 30 are connected, as just described, to form a hermetically sealed circuit in which I place a suitable volatile fluid. The coil 29, being embedded in the casting 25, is maintained at substantially the same temperature as 35 that of the casting, and, therefore, functions as a condenser in which the fluid condenses to liquid, the heat of condensation being transferred through the casting 25 to the coil 34 of the refrigeration apparatus. The liquid flows from the lower end of the condenser coil 29 into the leg 31 of the looped conduit 30.

The liquid would normally stand at the same level in legs 31 and 32 of the looped conduit 30. 40 However, when the temperature of the air in the refrigerator storage compartment rises above the vaporization temperature of the liquid in the secondary circuit, heat is transferred from the air through the fins 33 to the liquid in the leg 32 of the looped conduit 30. Thereupon, vapor is formed in the leg 32, causing the weight of the column of liquid in the leg 32 to become less than the weight of the column of liquid in the leg 31. The looped tube 30 is constructed and arranged 45 so that the difference in weight of the liquid columns in the legs 31 and 32 causes an upward flow of liquid in the leg 32 and into the upper end of the evaporator 26. This action is usually referred to as thermosyphon action. The leg 32 50 may be formed with an internal diameter sufficiently small so that liquid and vapor cannot pass each other therein, whereby liquid is raised through the leg 32 by an additional vapor lift or pumping action.

It will be understood that, as the temperature 55 of the air in the storage compartment 11 rises, the vaporization of liquid in the leg 32 will increase, causing a greater flow of liquid to the evaporator 26. In the evaporator 26, liquid evaporates, the heat of vaporization being transferred thereto from the air in the storage compartment through the extensive surface formed by the fins 27. The vapor returns from the evaporator 26 to 60 the condenser coil 29, completing the cycle in the

secondary circuit. The secondary cooling circuit may be arranged for operation at a desired temperature differential with respect to the temperature of the primary cooling element 14. For instance, a suitable fluid and an inert gas may be 5 introduced into the secondary system, so that evaporation of the fluid in the evaporator 26 takes place at a temperature above that of the primary cooling element at which condensation occurs in the condenser coil 29. The evaporator 26 10 may be provided with sufficient heat transfer surface, and operated at a temperature above that at which water freezes, thereby obviating the formation of frost thereon and the resulting decrease in humidity of the air. 15

Assuming that the refrigeration apparatus is in operation, the thermostat 19 may be adjusted by turning the knob 23 so that the refrigeration apparatus operates to maintain the cooling element 14, including the casting 25, at a desired 20 constant temperature. The primary cooling element 14 may be maintained at a temperature considerably below the freezing point of water, so that water or other substance in the ice trays 25 28 may be quickly frozen by direct conduction of heat from the trays to the shelves formed by the casting 25. Air in the refrigerator compartment 11 flows in contact with the outer surface of the casting 25 and becomes cooled thereby. However, the surface of the casting 25 is relatively small, 30 and, upon increase in heat loads, as upon increased heat leakage into the refrigerator, may be insufficient to maintain the air in the storage compartment 11 at the temperature desired for proper preservation of foods contained therein. The resulting increase in temperature of the air causes flow of liquid in the secondary circuit to the evaporator 26. The increased cooling surface of the evaporator 26, thus brought into effect, tends to maintain the temperature of air in the storage compartment at the desired temperature. 35 If the device is so constructed and arranged that the secondary circuit is at all times in operation, an increase in temperature of air in the storage compartment then results in increasing the supply of liquid cooling fluid to the evaporator 26 40 responsive to the increased demand for refrigeration. The result is that, for a given operating temperature of the primary cooling element 14, the air in the refrigerator storage compartment 50 is maintained at a substantially constant temperature. Furthermore, cooling of the air by the evaporator 26 is accomplished efficiently with a low temperature differential over an extensive 55 surface in the uppermost part of the storage compartment where the air is the warmest and the maximum temperature differential exists for a given temperature of the evaporator 26.

Various changes and modifications will be apparent to those skilled in the art, wherefore my invention is not limited to that which is shown in the drawings and described in the specification but only as indicated in the following claims.

What is claimed is:

1. In a refrigerator, a cabinet having a thermally insulated storage compartment, refrigeration apparatus including a cooling coil in said compartment and means for maintaining said cooling coil at a substantially constant temperature below freezing, a plain surface metal casting in which said cooling coil is embedded and which forms a receptacle for ice trays, a condenser coil also embedded in said casting, an evaporator above said condenser and comprising 75

- a. tube having an extensive surface formed by fins, a conduit for vapor from said evaporator to the upper end of said condenser coil, a downwardly looped conduit connected from the lower end of said condenser coil to said evaporator, a plurality of heat transfer fins on the leg of said looped conduit connected to said evaporator, and a volatile fluid in the circuit formed by said evaporator, condenser and looped conduit.
2. In a refrigerator, a cabinet having a thermally insulated storage compartment, refrigeration apparatus including a cooling element in said compartment, a metal casting in which said cooling element is embedded and which forms a receptacle for ice trays, a condenser coil also embedded in said casting, an evaporator above said condenser, a conduit for vapor from said evaporator to the upper end of said condenser coil, a conduit from the lower end of said condenser coil to said evaporator and forming a thermosyphon, and a volatile fluid in the circuit including said evaporator and condenser.
3. In a refrigerator, a cabinet having a thermally insulated storage compartment, refrigeration apparatus including a cooling element in said compartment, a metal casting in which said cooling element is embedded, a condenser also embedded in said casting, an evaporator above said condenser, conduit means interconnecting said evaporator and condenser in continuous circuit and forming a thermosyphon for raising liquid from said condenser to said evaporator, and a volatile fluid in said circuit.
4. A method of refrigeration which includes evaporating a first fluid in a place of thermal transfer relation with air to be cooled, condensing a second fluid by heat transfer to said first fluid, and delivering condensate of said second fluid to a certain further place of thermal transfer relation with said air to be cooled only upon rise in temperature of the air to be cooled.
5. A method of refrigeration which includes flowing air in thermal transfer relation with a plurality of places of evaporation, continuously supplying refrigerant fluid to one of said places of evaporation, and supplying refrigerant fluid to another of said places of evaporation in accordance with change in temperature of the air being cooled.
6. In a refrigerator having a thermally insulated storage compartment, a cooling element in thermal transfer relation with air in said compartment, means for maintaining said cooling element at a substantially constant temperature, and a circuit including an evaporator also in thermal transfer relation with air in said compartment, a condenser below said evaporator and in thermal exchange relation with said cooling element, a conduit for vapor from said evaporator to said condenser, and a downwardly looped conduit having one end connected to said condenser and the other end connected to said evaporator, said conduit forming a thermosyphon for causing flow of liquid from said condenser to said evaporator.
7. In a refrigerator having a thermally insulated storage compartment, refrigeration apparatus including a cooling element in limited thermal transfer relation with air in said compartment and means for maintaining said cooling element at a substantially constant temperature, a second cooling element in relatively extensive thermal transfer relation with air in said compartment, and means for supplying refrigerant fluid to said second cooling element responsive to change in temperature of air in said compartment.
8. In a refrigerator having a thermally insulated storage compartment, a plurality of evaporators in thermal transfer relation with air in said compartment, means for continuously supplying refrigerant fluid to one of said evaporators, and means for supplying refrigerant fluid to another of said evaporators in accordance with change in temperature of air in the compartment.
9. A refrigerator having a thermally insulated storage compartment, a cooling element in thermal contact with air in the compartment, means for supplying refrigerant to said cooling element, a second cooling element in thermal contact with air in the compartment, a condenser arranged in heat exchange relation with said first cooling element, and means connecting said second cooling element and said condenser to provide a closed fluid circuit containing a fluid adapted to condense in said condenser and evaporate in said second cooling element, said connecting means being so arranged and formed that fluid is supplied to said second cooling element from said condenser only when the said first cooling element is ineffective to maintain temperature of the air in the storage compartment at or below a predetermined value.
10. A refrigerator having a thermally insulated storage compartment, a cooling element in thermal contact with air in the compartment, means for supplying refrigerant to said cooling element, a second cooling element in thermal contact with air in the compartment, a condenser arranged in heat exchange relation with said first cooling element, and means connecting said second cooling element and said condenser to provide a closed fluid circuit containing a fluid adapted to condense in said condenser and evaporate in said second cooling element, said connecting means being so arranged and formed that fluid is supplied to said second cooling element from said condenser at a rate which is dependent upon the demand for refrigeration in the storage compartment.
11. A refrigerator having a thermally insulated storage compartment, a cooling element in thermal contact with air to be cooled, means for supplying refrigerant fluid to said cooling element, a second cooling element in thermal contact with air to be cooled, and means including said second cooling element forming an independent closed fluid circuit for supplying a second refrigerant fluid to said second cooling element at a rate dependent upon the temperature of the air in the storage compartment.
12. A method of refrigeration which includes the steps of continuously evaporating a first fluid in a place of thermal transfer relation with air to be cooled, condensing a second fluid by heat transfer to said first fluid, conducting the condensate of said second fluid to a second place of thermal transfer relation with air to be cooled in accordance with the demand for refrigeration determined by the temperature of the air to be cooled, and evaporating the condensate of said second fluid at the second place of thermal transfer relation with air to be cooled.
13. A refrigerator having a thermally insulated storage compartment, a cooling element in thermal contact with air in the compartment, means for supplying refrigerant to said cooling element, a closed fluid circuit including a second cooling element in thermal contact with air in

the compartment and a condenser connected thereto and arranged in heat exchange relation with said first cooling element, the fluid evaporating in said second cooling element and condensing in said condenser, said circuit including a part at a lower level than said second cooling element and connected thereto and to said condenser for accumulating condensate formed in the latter, said part being in thermal contact with air in the compartment and so formed and connected to said second cooling element that condensate formed in said condenser is supplied to said second cooling element only when said first cooling element is ineffective to maintain the air in the storage compartment at or below a predetermined temperature.

14. A refrigerator having a thermally insulated storage compartment, a cooling element in thermal contact with air in the compartment, means for supplying refrigerant to said cooling element,

a second cooling element disposed in the uppermost part of the compartment and at a higher level than said first cooling element, said second cooling element being in thermal contact with air in the compartment, a condenser arranged in heat exchange relation with said first cooling element, and means connecting said second cooling element and said condenser to provide a closed fluid circuit containing a fluid adapted to condense in said condenser and evaporate in said second cooling element, said connecting means being in thermal contact with air in the compartment and having a heat transfer surface and being so arranged and formed that condensate is supplied to said second cooling element from said condenser only when said first cooling element is ineffective to maintain the air in the storage compartment at or below a predetermined temperature.

ALBERT R. THOMAS. 20
